UNITED STATES PATENT OFFICE.

HERMAN C. KORFHAGE, OF NEW ALBANY, INDIANA.

CLOCK.

1,219,749.

Specification of Letters Patent.

Patented Mar. 20, 1917.

Application filed June 30, 1916. Serial No. 106,745.

To all whom it may concern:

Be it known that I, HERMAN C. KORFHAGE, a citizen of the United States, residing at New Albany, in the county of Floyd 5 and State of Indiana, have invented certain new and useful Improvements in Clocks, of which the following is a specification.

This invention relates to clocks, and more 10 particularly to tower clocks.

Tower clocks are of massive construction, and require very heavy weights to run them. The weights are suspended by means of cables or ropes, which are wound on 15 drums, the number of turns of the rope about the drum, determining the length of time the clocks will run with one winding, the drums being connected with the great wheel mounted on the same shaft as the drum, the great 20 wheel in turn meshing with a pinion on the central arbor, and imparting movement thereto. In order to avoid frequent re-winding, which is a laborious task, the suspension cables are of considerable length 25 necessitating deep wells or shafts for the descent of the weight, or a complicated set of pulleys, the use of which requires much heavier weights.

An object of this invention is the provision 30 of improved means of applying power to a clock train.

Another object is the provision of means whereby the tractive force of the weight is applied directly to the central arbor thereby dispensing with the winding drum, great 35 wheel and associated parts, with a consequent reduction of weight and friction.

Another object is the provision of mechanical means for raising the weight.

40 A further object is the provision of means whereby the weight raising means is controlled by the position of the weight.

With the foregoing and other objects in view the invention consists of the novel construction and arrangement of parts illustrated in the accompanying drawings, which form a part of this specification, wherein is set forth an embodiment of the invention, but it is to be understood that such changes 45 and modifications may be resorted to as come within the scope of the claims appended hereunto.

50 Referring now to the drawings, wherein similar reference characters designate like parts in the several views, Figure 1, is a front elevation of the time train of a tower

clock embodying my invention, the strike train being omitted for the sake of clarity: Fig. 2, a vertical longitudinal section on line 2-2 of Fig. 3: Fig. 3, a transverse section on line 3-3 of Fig. 1: Fig. 4, a perspective view of the electric switch mechanism: Fig. 5, a perspective view, on an enlarged scale, of one of the contact springs: Fig. 6, a section on line 6-6 of Fig. 4.

Referring now more in detail to the drawings, the reference numeral —10— designates a stand comprising legs —11— on which rests a rectangular base —12—. Erected on the base are two oppositely disposed frame members —13— connected at their upper ends by a transverse bar —14—. Clock mechanism being too well known to require extended description, suffice it to say that an arbor —15—, usually known as the central arbor, a second or intermediate arbor —16—, a third or scape arbor —17— and a fourth, or pallet arbor —18— are suitably and co-operatively mounted in the frame 13. The leaves of a wheel —19— on the central, or hour arbor, engage with those of a pinion —20— on the intermediate arbor, while those of a wheel —21— on the intermediate arbor engage with a pinion —22— on the scape arbor. A pallet —23—, 85 on the pallet arbor engages with an escape wheel —24— on the arbor 17. A crutch —25— depends from the pallet arbor, a pin —26— on the lower end thereof being engaged in a slot —27— in a pendulum rod 90 —28—. The hour arbor 15 extends exterior of the frame and carries on its outer end a minute hand —29— which travels over a dial —30—, an hour hand —31— being driven from the shaft 15 in the usual manner. Motion is transmitted from the arbor 15 by means of bevel gears —33—, 34— to a vertical shaft —32— which leads upward and transmits motion to dial mechanism on a tower above. A gimbal joint —35— serves 100 to compensate for any variations in alignment of the shaft 32. A contact spring —36— is secured on the pallet shaft 18 in such position that oppositely disposed fingers —37— on the escape arbor 17 may contact therewith periodically, thereby closing an electric current and transmitting impulses to subsidiary clocks distributed through the building. A sprocket wheel —40— is positioned on the hour arbor, a second sprocket wheel —41— is positioned on shaft —42—, forward of and preferably

on a lower level than the hour arbor and in alignment therewith. An endless sprocket chain —43— is disposed over these sprocket wheels depending therefrom. This sprocket 5 chain depends from the sprocket wheel 40 a suitable distance and is then brought up and passed over a sprocket wheel —44— secured on a shaft —45— forming a bight —46—. After passing over the sprocket 10 wheel 44, the chain drops forming a second bight —47— before it ascends to the sprocket wheel 41. Blocks —48, 49— to which weights may be attached, ride respectively in the bights 46 and 47. A worm- 15 gear —50 is secured on the shaft 45, and a worm —51— engaged therewith. The worm 51 may be driven by any suitable means such as an electric motor —52—, on the shaft —53— of which it is mounted. 20 The motor is suspended from the base 12 by suitable means such as a bracket —54—, the forward end of the shaft 53 being carried by a bracket —55—. A weight, as —56— is suspended from the block 48 and 25 exerts tractive force, equally through the sprockets 40 and 44, upon the shafts 15 and 45 but movement of the shaft 45 is prevented by reason of the engagement of the worm with the worm-gear. The pulley 49, 30 in the bight 47 carries sufficient weight, and is intended only, to keep the chain taut. It is obvious that the effective force applied to each of the shafts is only half of the weight carried in the bight 46, and that said 35 force is constant regardless of the length of the bight or changes in its length, consequently the weight may be raised at any time without retarding the clock movement. The weight is raised through the medium 40 of the electric motor, by turning the shaft 45, and sprocket 44 thereby shortening the bight 46 and consequently lengthening the bight 47. The electric motor is controlled by means of a switch —60— which is actuated periodically by means of projections, or teeth —61—, on the edge of the chain. The switch 60 comprises a base-plate —65— of suitable material, such as fiber, attached to the face of which are contact blocks, or 50 segments —66— having provision for the connection thereto of electrical conductors, and rotary brushes —67— which are adapted to be brought into contact with the contact-blocks, thereby completing an electric 55 circuit through and energizing the motor. As illustrated herewith the base plate is secured on a stud —68—, which projects from the base 12. The brushes are mounted on posts —69—, which are set in a collar 60 —70— formed about a rotatable spindle —71—, which is mounted on the stud, forward of the base-plate. Springs —72— disposed about the posts and bearing respectively against the collar 70 and the brushes 65 insures firm contact of the brushes with the

contact-plates. At the outer end of the spindle is a flange —73— extended from the forward face of which are a plurality of pins —74—, similar pins —75— being extended from the rear face thereof. The 70 switch is so positioned that the pins 74 will lie between the descending limb —62—, and the ascending limb —63—, of the chain, and in such relationship thereto that the teeth 61 which project therefrom will engage successively and periodically with said pins during both the descending and ascending movements of the chain. Guide-plates —64— are so positioned as to bear against the back of the chain at such points as will insure that the chain will maintain its position when the teeth 61 engage with the pins 74. A spring —76— bears against the pins 75 and serves to prevent any overthrow in the movement of the brushes and to maintain them in adjusted position. As the limb 62 of the chain descends under the influence of the weight 56, a tooth 61 will engage with a pin 74, and give the spindle a quarter turn, bringing the brushes into contact with the plates, thereby closing the motor circuit and starting up the motor. The motor rotates the sprocket wheel 44 which draws up the ascending limb 63, of the chain, shortening the bight 46, and raising the weight 56. 85 This movement continues until an ascending tooth 61, in the limb 63, engages with a pin 74 on the spindle, giving the spindle a further quarter turn, thus moving the brushes from the contact blocks, breaking the motor circuit and stopping the motor. The chain may be of any desired length, but I consider it desirable to have it of such length that it will run the clock for a period of more than 24 hours, say 36 hours, without 100 the weight being raised, in order that the clock would not stop prematurely in case of accident, such as a tooth being broken off the chain, or the electric current being interrupted. The projections, or teeth may be 105 spaced at any desired intervals about the chain so that the weight may be raised frequently and be normally near the upper limit of its travel. Should a tooth be broken off the chain, the switch 60 would not be 110 thrown at the proper time, as the weight was being raised, and the weight would be drawn up against and damage the switch mechanism. To avoid this, I place an electric switch —77—, which is interposed in the 115 motor circuit, preferably a single pole single throw switch, in such a position that its handle extends into the path of the weight and is raised thereby, to open the motor circuit, and stop the ascent of the weight 120 before it reaches a point where it will cause damage. The blocks 48, 49 each comprise a sprocket wheel —80— pivotally mounted within a shell the cheeks —81— of which 125 extend beyond the circumference of the 130

sprocket wheel a spaced distance sufficient to prevent the block from being accidentally displaced on the chain. While I have herein described my improvement as applied to the time train, it is to be understood that it is equally applicable to the strike train. It will be clear to a person conversant with the art that my improved construction dispenses with many parts, with a consequent diminution of friction, thus requiring a smaller weight to run the clock and reducing the total weight of the clock, thus making it more compact and economical in construction than those now in use.

Having thus described my invention so that anyone skilled in the art pertaining thereto may make and use the same,

I claim:

1. In a clock movement, a plurality of sprocket wheels, an endless chain disposed on and depending from said wheels, a weight adapted to ride in a bight formed by said depending chain, a motor for shortening said bight and raising said weight, and means adapted to be actuated by a descending portion of the chain to render said motor operative, and by an ascending portion thereof to render it inoperative, said means comprising an electric switch consisting of a base plate, contact blocks thereon, a spindle rotatably mounted in front of said plate and carrying brushes adapted to bear on said block and pins extended from the forward end of the spindle.

2. In a clock movement, a sprocket wheel mounted on an arbor thereof, an endless chain disposed on said wheel and depending therefrom, a sprocket wheel mounted on a lower level, said chain being looped up and its outer periphery passed over said second named wheel thereby forming bights on each side thereof, a weight for driving the clock train riding in one of said bights, an electric motor, operative connections between said motor and the second wheel for turning said wheel and raising the weight, an electric switch adapted to control the motor, said switch comprising a base plate, contact blocks thereon, a spindle rotatably mounted in front of said base plate and carrying brushes which bear on said blocks, pins extended from the forward end of the spindle and lying between the limbs of a bight, and projections on the chain adapted to engage with said pins.

3. In a clock movement, a sprocket wheel mounted on an arbor thereof, an endless chain disposed on said wheel and depending therefrom, a sprocket wheel mounted on a lower level, said chain being looped up and its outer periphery passed over said second named wheel thereby forming bights on each side thereof, a weight for driving the clock train riding in one of said bights, an electric motor, operative connections between said

motor and the second wheel for turning said wheel and raising said weight, an electric switch comprising a base plate, a rotatable spindle extended therefrom and carrying brushes which bear on the plate, pins extended from the forward end of the spindle and lying between the limbs of the bight carrying the driving weight, projections on the chain adapted to engage with said pins to throw the switch, and a switch adapted to be actuated by the weight at the limit of its upward movement to render the motor inoperative.

4. In a clock movement, a sprocket wheel mounted on the main arbor thereof, an endless chain disposed on said wheel and depending therefrom, a sprocket wheel mounted on a lower level, said chain being looped up and its outer periphery passed over said second named wheel thereby forming depending bights on each side thereof, a weight for driving the clock train riding in one of said bights, an electric motor, operative connections between said motor and the second wheel for turning said wheel and raising the weight, an electric switch comprising a base-plate, contact blocks thereon, a spindle rotatably mounted in front of said base-plate and carrying brushes which bear on the plate, pins extended from the forward end of the spindle and lying between the limbs of the bight carrying the driving weight.

5. In a clock, an arbor, a sprocket wheel mounted thereon, a second arbor carrying a sprocket wheel, an endless sprocket chain depending from said sprocket wheels, a weight adapted to ride in a bight formed by said depending chain, a motor for shortening said bight and raising said weight, an electric switch comprising a base plate, contact blocks thereon, a spindle rotatably mounted in front thereof, brushes carried by said spindle and bearing on the blocks, a flange on the forward end of the spindle, pins extended from the face of the flange in planes parallel with the axis of the spindle, and lying between the limbs of a bight, and means whereby one limb of the bight engages with said pins and actuates the switch to energize the motor and the other limb of the bight actuates the switch to deenergize the motor.

6. In a clock, an arbor, a sprocket wheel mounted thereon, a second arbor carrying a sprocket wheel and an endless sprocket chain depending from said sprocket wheels, a weight adapted to ride in a bight formed by said depending chain, a motor for shortening said bight and raising said weight, means adapted to be actuated by a descending portion of the chain to render said motor operative and by an ascending portion to render it inoperative, said means comprising an electric switch consisting of a base-plate, a spindle rotatably mounted in front of said

plate, posts extended radially from the spindle, brushes mounted on said posts and adapted to bear on the plate, a flange on the forward end of the spindle, and a plurality of pins extended from the face of the flange in planes parallel with the axis of the spindle.

7. In a clock movement, a sprocket wheel mounted on the main arbor thereof, an endless chain disposed on said wheel and depending therefrom, a sprocket wheel mounted on a lower level, said chain being looped up and its outer periphery passed over said second named wheel thereby forming de-

pending bights on each side thereof, a weight 15 for driving the clock train riding in one of said bights, an electric motor, operative connections between said motor and the second wheel for turning said wheel and raising the weight, an electric switch, comprising a base 20 plate, a rotatable spindle extended therefrom and carrying brushes which bear on the plate, pins extended from the forward end of the spindle and lying between the limbs of the bight carrying the driving weight, 25 and projections on the chain adapted to engage with said pins to throw the switch.

HERMAN C. KORFHAGE.
